UNITED STATES PATENT OFFICE

HARRY E. TOWNSEND, OF BROOKLYN, NEW YORK

WRAPPING MACHINE

Application filed December 9, 1925. Serial No. 74,293.

My invention relates to machines for handling and wrapping articles, and has special reference to machines for wrapping hard candies and other articles that are in the form 5 of circular disks.

An object of the invention is to provide a machine of this character which is simple in construction, and rapid and efficient in operation.

10 Another object of the invention is to provide a machine for wrapping a substantially cylindrical article, such as a roll of hard candies, in a novel and improved manner.

Another object of the invention is to provide 15 novel and improved mechanism for handling articles such as hard candies that are in the form of circular disks.

With these and other objects in view, the 20 features of the invention consist in certain constructions, arrangements and combinations of parts hereinafter described and claimed, the advantages of which will be obvious to those skilled in the art.

The several features of the invention will 25 be clearly understood from the following description and accompanying drawings, in which:

Figure 1 is a longitudinal sectional view 30 of the upper portion of a machine embodying certain features of the invention;

Fig. 2 is a plan view partly diagrammatical of a portion of the article handling devices of the machine and showing the articles in the position they assume as they are delivered 35 to the machine;

Fig. 3 is a diagrammatical longitudinal sectional view of the same but showing the parts in a different position from that shown in Fig. 1;

40 Fig. 4 is a right side elevation on an enlarged scale of the upper portion of the machine;

Fig. 5 is a similar view of the opposite side of the machine;

45 Fig. 6 is a sectional view taken substantially on the line 6—6 of Fig. 4;

Fig. 7 is a sectional plan view taken on the line 7—7 of Fig. 4;

50 Fig. 8 is a sectional view, on an enlarged scale, taken on the line 8—8 of Fig. 6;

Fig. 9 is a transverse sectional view taken on the line 9—9 of Fig. 4;

Fig. 10 is a detail view in perspective, partly broken away, showing a part of the wrapper folding or tucking-in mechanism of 55 the machine;

Fig. 11 is a vertical sectional view, on an enlarged scale, taken substantially on the line 11—11 of Fig. 1;

Fig. 12 is a longitudinal sectional elevation 60 of the lower portion of the machine;

Fig. 13 is a transverse sectional view taken on the line 13—13 of Fig. 12;

Figs. 14, 15 and 16, are diagrammatical 65 views of a portion of the wrapping mechanism and illustrating different steps as performed by the machine in placing the wrapper about the peripheral surface of the roll of candies or other article;

Fig. 17 is a rear end elevation, partly diagrammatical of a portion of the wrapping mechanism shown as operating upon the article in tucking in the ends of the wrapper 70 over the ends of the roll;

Fig. 18 is a view in perspective of the completed package;

Figs. 19 and 20 are detail face and side views, respectively, of an end tucking device 75 of the machine;

Figs. 21 to 25, inclusive, are views in perspective of one end portion of the article with the wrapper applied thereto, and showing successive steps as performed by the machine in folding or tucking in the projecting 80 ends of the wrapper over the ends of the article;

Fig. 26 is a side elevation of a mechanism for connecting the wrapping machine with another wrapping machine for placing a second wrapper about the article, the two machines being indicated by broken lines;

Fig. 27 is a longitudinal sectional view, partly diagrammatical, illustrating another form of wrapping mechanism that may be employed;

Fig. 28 is a view corresponding to a portion of Fig. 27, showing the position of certain parts of the wrapping mechanism at another stage in the wrapping operation;

Fig. 29 is a rear elevation, partly diagram-

matical, of a portion of the wrapping mechanism illustrated in Fig. 27;

Fig. 30 is a sectional elevation showing another form of mechanism for delivering the articles to the machine;

Fig. 31 is a rear elevation with certain parts removed of the mechanism illustrated in Fig. 30; and

Fig. 32 is a sectional plan view taken on the line 32—32 of Fig. 30.

The machine illustrated in the drawings is particularly adapted for use in handling and wrapping articles 2 such as hard candies that are in the form of circular disks. As shown, the articles are supplied to the machine from downwardly inclined raceways or chutes 4 which are arranged side by side, the articles in each chute being arranged one behind the other. Suitable devices, including an escapement 6 are provided for causing the lowermost articles in the several chutes to be removed therefrom and to advance downwardly by gravity against a stop member 8. Because of the thickness of the walls between the several chutes, the articles thus positioned against the stop member 8 are spaced some distance apart, as shown in Fig. 2, but before they have a chance to topple over, collector fingers 10 (Figs. 1 and 9) are advanced toward each other and by engagement with the endmost articles of the row bring the several articles together. While the row of articles is thus held by the collector fingers 10, gripping jaws 12 advance and grip the ends of the row, whereupon the collector fingers are retracted from the row. The gripping jaws are then moved upwardly to carry the row of articles above the stop member 8, then swung in a clockwise direction, and then moved upwardly and forwardly to present the row of articles to the wrapping mechanism of the machine. This wrapping mechanism comprises upper and lower wrapping rolls 14 and 16, respectively, which are arranged in parallel relation and spaced apart, the gripping jaws positioning the row of articles between the wrapping rolls with the axis of the row substantially in the plane of the axes of the rolls. During the first part of this transfer movement of the row of articles from the station adjacent the stop 8 to the wrapping rolls, a strip of paper or other wrapping material is fed downwardly from a roll 17 by means of feed rolls 18 so as to position the lower end portion of the strip across the path of movement of the row of articles and in proximity to the wrapping rolls 14 and 16. Before the row of articles reaches the strip of wrapping materials, a sheet 19 of suitable size to form the wrapper for the row of articles is cut off from the strip by shearing blades 20 and 21, the lower portion of the severed wrapper being supported in upright position in a suitably ar-

ranged basket 22. The row of articles upon engagement with the upper portion of the wrapper carries the wrapper therewith to its position between the wrapping rolls and during this movement the upper portion of the wrapper is bent over the forward portion of the row by a member 23 and an upwardly spring pressed plate 24 between which the row passes. The row of articles is held in position between the wrapping rolls by retaining fingers 25 which advance toward each other into engagement with the ends of the row. After the row of articles is positioned between the wrapping rolls, the member 23 acts to tuck in the upper edge portion of the wrapper over the back of the row of articles. As this upper edge portion of the wrapper is being tucked in, retaining rolls 26 and 28 are brought downwardly so as to engage opposite sides of the peripheral portion of the row of articles and wrapper in proximity to the upper wrapping rolls 14. The wrapping rolls 14 and 16 are then rotated in a counter-clockwise direction so as to rotate the row of articles and its wrapper in a clockwise direction and thus cause the wrapper to be tightly wrapped about the peripheral surface of the articles. Preferably, the wrapper is of suitable length and the row of articles is rotated a sufficient number of times to cause the wrapper to be wound slightly more than twice around the row. When the wrapper has thus been applied, devices 30 act to tuck in the ends of the wrapper over the ends of the row to complete the wrapping operation. A second pair of gripping jaws 32 (Fig. 26) are then advanced to engage the ends of the package thus formed and to convey the completed package from the wrapping mechanism, the retaining rolls 26 and 28 being retracted as the gripping jaws advance into engagement with the package, and the upper roll 14 being retracted from the package previously to the removal of the package from the wrapping rolls.

The escapement 6 comprises a bar that extends transversely over the lower end portions of the chutes 4 and is provided with depending ears on its ends that are secured on pivot shaft 34 which extend through pivot bearings in upstanding ears 36 on a plate 38 that forms the bottom of the chutes. The pivot shafts 34 are in alignment and have their axis substantially in the plane of the axes of the articles in the chutes, and the underside of the escapement bar is transversely curved concentrically with the axis of the pivot shafts, the radius of the curvature being slightly greater than the radius of the articles.

The stop member 8 is arranged above and across the bottom plate 38, and is secured on a pivot shaft 40 which extends through bearings in the upper ends of upstanding ears 42 on the plate 38.

With the parts in the position shown in Fig. 1, a row of articles is positioned against the stop member 8, and the escapement 6 is in engagement with the lowermost articles in the several chutes so as to hold them back. After the collector fingers 10 have acted to bring the articles in the row together, and the gripping jaws 12 have acted to remove the row to convey it to the wrapping mechanism, the escapement 6 is swung downwardly into the position shown in Fig. 3, which permits the articles in the several chutes to advance by gravity until the lowermost articles engage the curved under surface of the escapement, and simultaneously with such movement of the escapement the stop member 8 is swung upwardly out of stopping position. This retracting movement of the stop member 8 is for the purpose of permitting the row of articles to be discharged from the machine in case the gripping jaws fail to remove them, the gripping jaws being so constructed that they will only engage and remove the row of articles when there are a certain number of articles in the row. A suitable discharge chute, not shown, may be provided to receive the articles that are thus released by the stop member 8 and to convey them from the machine. After the escapement 6 and stop member 8 have remained in the position shown in Fig. 3 a sufficient length of time to permit the lowermost articles in the several chutes to advance by gravity into engagement with the under side of the escapement, the escapement and stop member 8 are simultaneously returned to the position shown in Fig. 1, this movement of the escapement releasing the lowermost articles in the chutes so as to permit them to advance into engagement with the stop member, and engaging the lowermost articles remaining in the chutes so as to hold them back.

The escapement 6 and stop member 8 are actuated by means of rods 44 and 46 having their upper ends pivotally connected with arms 48 and 50 secured to one of the pivot shafts 34 of the escapement and to the pivot shaft 40 of the stop member 8, respectively. The lower ends of the rods 44 and 46 (Fig. 12) are both pivotally connected with one end of a lever 52 which is pivotally mounted on a hanger 54 secured to a base plate 56 of the frame of the machine, and has a cam roll 58 on its other end that engages a cam 60 carried by a shaft 62. The shaft 62 is journaled in suitable bearings in the machine frame and is continuously driven by the main driving shaft 64 of the machine through bevel gears 66 secured on the shafts, respectively. The collector fingers 10 (Figs. 1 and 9) for bringing the articles together after they are advanced into position against the stop member 8, are provided with narrow heads 68 which are arranged transversely at right angles to the supporting plate 38, and their inner or article engaging surfaces are inclined slightly downwardly and outwardly so that when they engage the ends of the row of articles they apply a slightly greater pressure at the upper portion of the row than at the lower portion, and thus tend to cause the articles to tightly bear upon the supporting plate 38. This is particularly advantageous in case the sides of the articles are slightly convex which frequently occurs with hard candies.

The collector fingers 10 are mounted to slide toward and from each other on the supporting plate 38 and are guided by suitable bearings 70 secured on the plate. The fingers are adapted to be thus actuated to engage and disengage the ends of the row of articles in proper timed relation to the operation of the other article handling devices, by means of an upstanding rocker arm 72. The left hand collector finger 10, viewing Fig. 9, is directly secured to the rocker arm 72 by means of a reduced end portion 74 thereof which extends through an aperture in the rocker arm, and held in position by means of a shoulder 76 thereof engaging one side of the rocker arm and nuts 78 screw-threaded on the outer end thereof against the outer side of the rocker arm. The connection between the other collector finger 10 and the rocker arm comprises a rod 80 which is secured to the outer end of the finger and extends through a bearing in an upstanding bracket 82 on the base plate 56. The upper forked end of a lever 84 operatively engages laterally projecting pins 86 secured to the rod 80. The lever 84 is pivotally mounted at 88 on the bracket 82 and its lower end is connected with the rocker arm 72 through a rod 90, having one end pivotally connected with the rocker arm and its other end extending through an aperture in the lower end of the lever. A spring 94 is coiled about the rod 90, and is interposed between a collar 96 secured on the rod and the lower end of the lever 84, the spring tending to hold the lower end of the lever against abutment nuts 98 secured on the end of the rod. With this construction, upon movement of the rocker arm 72 in a clockwise direction, viewing Fig. 9, the collector fingers 10 will be moved toward each other, the left hand collector finger being positively moved by the rocker arm, and the other finger being yieldingly moved through the coiled spring 94. The rocker arm 72 extends through an aperture in the base plate 56 and is pivotally mounted at 100 on a bracket member depending from the base plate, and its lower end (Figs. 12 and 13) is provided with a cam roll 102 that engages a suitable cam 104 carried by the driven shaft 62, the cam roll being held against the cam surface by means of a coiled spring 106 connected with the lower end of the rocker arm lever.

The gripping jaws 12 which, as above described, move down and grip the ends of the row of articles immediately after the articles are brought together by the collector fingers 10 are provided with slotted ends to permit them to clear the collector fingers and engage the ends of the row of articles previously to the retraction of the fingers. These gripping jaws are mounted upon a block 108 (Fig. 9) 5 which has upstanding ears 110 that are secured on a pivot pin or shaft 112 which extends through and is pivotally mounted in a bearing in the rear end of one arm of a carrier lever 114. The left hand gripping 10 jaw viewing Fig. 9, is rigidly secured to the supporting block 108 by a screw 116, and the other gripping jaw is secured on one end of a pin 118 which extends through and is mounted to slide in apertures in said upstanding ears 110. The pin 118 is pressed in 15 a direction to move the right hand jaw toward the other jaw, by means of a spring 120 coiled about the pin and interposed between a collar 122 secured on the pin, and the inner side 20 of the right hand ear 110. The movable jaw 12 is held from turning movement by means of a pin 124 secured thereto which extends into a guiding groove in the under side of the supporting block 108. The movement of 25 the jaw by the action of the spring 120 is limited by the engagement thereof with the side of the block. During the movement of the jaws into position to permit them to engage the ends of the row of articles, the outer 30 end of the jaw carrying pin 118 engages a suitably inclined surface on a cam plate 126 secured to the upper end of the rocker arm 72, which causes the pin to be forced in a direction to move the right jaw away from 35 the other jaw, so as to permit the two jaws to pass across the ends of the row of articles. When they have reached the limit of this movement the rocker arm 72 and the cam plate 126 carried thereby are retracted to 40 permit the jaws to close upon the ends of the row. As the rocker arm 72 is thus retracted the collector fingers 10 are moved thereby out of engagement with the row of articles as the row is gripped by the jaws. 45

In case there are less than the desired number of articles in the row, the gripping movement of the movable jaw is arrested by the engagement thereof with the side of the supporting block 108 so that it will not move in 50 sufficiently to engage the short row of articles and thus the jaws will not remove the row, but they will continue their cycle of operations.

The carrier lever 114 is pivotally mounted 55 upon a shaft 128 which is supported and journaled in suitable bearings in side frames 130 mounted upon the base plate 56. A bell crank 132 is pivotally mounted at 134 on the rear or jaw carrying arm of the lever 60 114. One arm of this bell crank 132 is pro-

vided with a gear segment 136 that operatively engages a pinion 138 secured on one end of the pivot shaft 112. The other arm of this bell crank 132 carries a cam roll 140 which engages a cam groove 142 in a bracket 70 secured to one of the side frames 130. The cam groove 142 is so shaped that during the upward movement of the carrier of the lever arm 114 and after the row of articles carried by the gripping jaws has passed a distance 75 above the supporting plate 38, the bell crank 132 is turned in a direction to act through the pinion 138 to turn the supporting block 108 and the gripping jaws carried thereby in a clockwise direction to substantially reverse 80 the position of the jaws, and during the continued movement of said lever the jaws are advanced substantially in a horizontal plane 85 to position the row of articles between the wrapping rolls 14 and 16.

It will be apparent that during the return movement of the carrier lever 114, the gripping jaws traverse the same path as during their advancing or article conveying movement.

The carrier lever 114 is connected through a link or rod 144 with one end of a cam lever 146 (Figs. 12 and 13) pivotally mounted on the machine frame and provided with a cam roll 148 which engages the groove of a cam 90 150 carried by a shaft 152. The shaft 152 is journaled in bearings in the machine frame, parallel with the shaft 62, and is connected with the main drive shaft 64 through bevel gears 154 secured on the two 100 shafts, respectively.

The roll 17 of wrapping material (Figs. 1 and 11) is carried by a spool 156 which is suitably mounted for rotary movement upon a stud shaft 158 secured to a bracket at the upper end of one of the uprights or side frames 130. The spool and roll is prevented from overrunning by means of any suitable tensioning device 159 engaging the spool. The strip of wrapping material is drawn 105 from the roll and passed downwardly over a suitable guide roll 160 and between the feed rolls 18 and the cutting off knives 20 and 21. The feed rolls 18 are secured on shafts 162 and 163. The shaft 162 is journaled in fixed bearings in the side frames 130. The shaft 163 is journaled in bearings in the upper ends of supporting arms 164 that are pivotally mounted on shafts 166 which extend through bearings on the side frames 110 130. A hand-operated lever 168 (Figs. 5 and 11) is pivotally mounted upon the upper end of each of the supporting arms 164 and a link 170 has one end pivotally connected with the lever 168 midway of its ends and its other end pivotally connected with a bell crank 172 pivotally mounted on the side frame 130. A coiled spring 174 tends to turn the bell crank 172 in a counter clockwise direction, viewing Fig. 5. With this 115 120 125 130

construction, when the hand operated levers 168 are swung downwardly into the position shown in Fig. 5, the links 170 are positioned below the pivotal connections between the levers 168 and the supporting arms 164, which permit the springs 174 to act through the bell cranks 172, links 170 and levers 168 to turn the supporting arms 164 in a direction to press the movable feed roll toward the other roll. A laterally projecting pin 176 on each of the levers 168 enters a notch on the under side of the link 170 to lock the link and lever together when the parts are in the position shown in Fig. 5. The feed rolls 15 may be separated by merely swinging upwardly the hand-operated levers 168.

Pinions 180 are secured on the left hand ends of the feed roll shafts 162 and 163. The pinion on the feed roll shaft 162 engages an idle gear 182 which in turn engages a gear 184. The pinion 180 on the movable feed roll shaft 163 engages a pinion 186 which is loosely mounted on the right hand pivot shaft 166 of the feed roll supporting arm, 25 and this pinion in turn engages said idle gear 182. It will be apparent that upon rotation of the gear 184, the two feed roll shafts 162 and 163 may be rotated in opposite directions to feed the strip of wrapping material between them, and also that the construction is such as to permit the feed rolls to be separated, by swinging the hand-operated levers 168 upwardly without disengaging the movable feed roll from its driving mechanism.

35 The gear 184 is secured on the outer end of a shaft 188 which extends through and is journaled in a bearing in the side frame 130. An arm 190 (Fig. 1) is secured upon the inner end of the shaft 188 and carries a pawl 192 which is pressed by a spring 194 into engagement with a ratchet wheel 196. This ratchet wheel 196 is loosely mounted upon the shaft 188 and is carried by a gear 198 which is operatively engaged by a rack 200 mounted to slide in suitable vertical bearings on the side frame 130. The ratchet wheel 196 is provided with a single tooth 202 which upon upward movement of the rack 200 engages the tooth of the pawl 192 and 50 acts through the pawl and arm 190 to rotate the shaft 188 in a direction to cause the feed rolls 18 to feed the strip of wrapping material downwardly between them, and that during the downward movement of the rack 200 the ratchet tooth of the ratchet disk 196 disengages from the pawl 192 and thus no movement is imparted to the feed rolls.

55 The rack 200 extends downwardly through an opening in the base plate 56 of the machine frame and its lower end is connected by a short link 204 with one end of a cam lever 206 pivotally mounted on the machine frame and carrying on its other end a cam roll 208 that engages a cam groove in a cam 60 210 carried by the shaft 152.

The strip of wrapping material is guided during its passage from the feed rolls 18 to the cutting off knives 20 and 21 by means of vertical guide wires 212 which have their upper ends received in annular grooves in the feed rolls and their lower ends secured to plates 214 which in turn are suitably secured to a supporting bar 216 that extends between and is secured to the side frames 130.

70 The shearing blade 20 is rigidly secured to the under side of a block 218 which in turn is secured to the under side of the transverse supporting bar 216. The cooperating blade or knife 21 (Figs. 4 and 7) extends through an opening in the right hand side frame 130 and is pivotally mounted on the lower end of a vertical pivot pin 220 which extends upwardly through a bearing block 222 secured on the outer side of the side frame. The pivot pin 220 is urged upwardly by a spring 224 coiled about the pin and interposed between the upper end of the block 222 and nuts 226 screw-threaded on the upper end of the pin. The knife 21 is adapted to be turned about the pivot pin 220 to cause it to cooperate with the stationary knife 20, by means of a horizontal bar 228 which is mounted to slide in suitable bearings on the inner side of the side frame 130. The bar 228 is connected with the cutting off knife by means of a bolt 230 which has its lower end secured to the blade, and extends through an aperture in the forward end of the sliding bar. A spring 232 is coiled about the bolt 230 and is interposed between the top side of the bar 228 and nuts 234 on the upper end of the bolt. The two springs 224 and 232 tend to press the lower knife blade 21 upwardly against the other blade. During the cutting off movement of the lower knife blade, the upper end of a pin or screw 236 rides on an inclined surface 238 on the lower end of the bearing block 222 so as to tend to cause clearance at the outer ends of the blades and thus permit cutting pressure at the inner ends of the blades.

75 The sliding bar 228 is reciprocated to open and close the cutting off knives by means of an arm 240 having its upper end connected with the bar through a pin and slot connection, and its lower end secured to the inner end of a pivot shaft 242 which extends through a bearing in a bracket 244 secured on the side frame 130. An arm 246 is secured on the outer end of the shaft 242 and is connected by a rod or link 247 with one end of a lever 248 pivoted on the side frame and carrying a cam roll 250 that engages a cam 252 carried by the outer end of the shaft 128. The cam roll is held in engagement with the cam by means of a spring 254 coiled about the link or rod 247 and interposed between a nut 256 secured on the rod and a bracket member 258 secured to the side frame and having a slot through which the rod or link slides.

The basket 22 for receiving the wrapper after it is cut off by the knives 20 and 21 and for holding it in upright position across the path of movement of the row of articles as 5 they are being transferred to the wrapping rolls, is provided with a suitable mouth piece 260 (Figs. 1 and 11) arranged adjacent the under side of the knives and held in position by vertical supporting strips 262 that are se- 10 cured at their lower ends to a bracket member 264 projecting from one of the side frames 130. The bracket member 264 is provided with forward projections 266 on which the lower portion of the wrapper guiding plate 15 24 that assists in guiding the wrapper from the basket to the wrapping rolls, is secured by screws 268. These screws 268 extend through slots in the plate 24 to permit the plate to be yieldingly pressed upwardly by means of 20 coiled springs 270 having one end secured to the plate and their other ends secured to the forward side of the mouth piece 260. The upper portion of the plate 24 is bent forwardly and extends substantially to the upper 25 portion of the surface of the lower wrapping roll 16. The lower portion of the basket is formed by strips 272 having their upper ends secured to the rear side of the bracket member 264 and having their lower ends bent for- 30 wardly at right angles to form the bottom of the basket. Strips 274 are secured at their upper ends to the lower portion of the yield- ing plate 24 and having their lower ends ar- ranged adjacent the lower ends of the strips 35 272 so as to form the forward wall of the lower portion of the basket.

The centering fingers 25 (Fig. 6) which engage the ends of the row of articles when the articles are positioned between the wrap- 40 ping rolls 14 and 16 by the gripping jaws 12, to hold the row in position when the jaws are released, are in the form of inwardly spring- pressed plungers that are mounted in sockets in the inner ends of rods 276, the fingers being 45 adapted to pass through the slots in the ends of the jaws. The rods 276 are mounted to slide through bearings in the side frames 130 and are actuated to move the fingers toward and from each other to engage and disengage 50 the ends of the row of articles, by means of levers 278 pivotally mounted on brackets pro- jecting from the side frames 130 and having their upper ends suitably connected with the outer ends of the rods, and their lower ends 55 provided with cam rolls 280 that engage the grooves in barrel cams 282 secured on the ends of the shaft 128. This shaft is driven by a chain 284 which passes over sprocket wheels secured on the shaft 62 (Figs. 12 60 and 13).

One of the finger carrying rods 276 has a bar 286 secured transversely thereon, which acts when the fingers are moved toward each other to engage the end of the movable jaw 65 carrying pin 118 to open the jaws and to

maintain the jaws open as they are retracted.

The lower wrapping roll 16 (Figs. 1 and 6) is centrally secured upon a shaft 288 which extends through and is journaled in bearings in the side frames 130. The upper wrapping roll 14 is secured on the end of a shaft 290 which extends through and is journaled in a bearing sleeve 292 that in turn extends through a block or arm 294 pivotally mounted on a stud shaft 296 (Fig. 8) which extends through and is secured to one of the side frames. The two wrapping roll carrying shafts 288 and 290 are both driven by a gear 298 (Fig. 5). The lower roll shaft 288 is connected with the gear 298 through a pinion 300 secured on one end thereof outside of the side frame which engages an idle gear 302 which in turn is engaged by the gear 298. The upper roll carrying shaft 290 is connected with the gear 298 through a pinion 304 se- 30 cured on its outer end which engages an idle gear 306 loosely mounted on said stud shaft 296, and engaging the gear 298. The mounting of the gear 306 on the stud shaft 296 that carries the swinging arm 294, permits the 35 upper feed roll to be raised and lowered without disturbing the driving connection therewith.

The gear 298 is loosely mounted on a shaft 308 which carries a ratchet disk 310 having a single tooth that is adapted to operatively engage the tooth of a spring pressed ratchet pawl 312 carried by the gear, so as to connect the gear to the shaft 308 upon rotation of the shaft in one direction to drive the wrapping rolls and to disconnect the gear and shaft upon rotation of the shaft in the opposite direction. The shaft 308 extends through and is journaled in a bearing in the side frame 130 and is driven by a gear 314 secured on its inner end that engages the vertical rack 200. With this construction it will be apparent that through their connection with the rack 200, the wrapping rolls 14 and 16 and the wrapper feeding rolls 18 may be actuated in harmony, so that during the wrapping operation upon one row of articles, the strip of wrapping material may be fed down and a wrapper cut off in position to be engaged and carried into the wrapping rolls by the 100 next succeeding row of articles.

The retaining rolls 26 and 28 are loosely mounted on rods or shafts 316 and 318, re- spectively. The shaft 316 is carried by the ends of arms 320 (Figs. 1, 6, 7 and 8) that are pivotally mounted on the bearing sleeve 292 at opposite sides of the swinging block or arm 294 that carries the upper feed roll 14. The shaft 318 is carried by the ends of arms 322 that are pivotally mounted on the bearing sleeve 292, and interposed between the swinging block or arm 294 and the arms 320, the upper ends of the arms 322 being secured together by a pin 324 so as to cause them to move together. The roll carrying shafts 316 115

and 318 are both connected by links 326 with the outer end of a lever 328 (Fig. 8) which is pivoted on one of the side frames 130 and is provided with a cam roll that engages a cam 330 carried by the shaft 128, the cam roll being urged toward the cam by a coiled spring 331 connected with the cam lever 328.

With the parts in the position shown in Fig. 8, the upper feed roll is in its highest position above the lower roll, and the retaining rolls 26 and 28 are in their highest positions. The swinging block or arm 294 that carries the upper wrapping roll, is pressed downwardly by means of a downwardly spring pressed rod 332, but in the position shown in Fig. 8 the swinging arm is held from downward movement by the engagement of an abutment screw 334 with a collar 336 secured on the retaining roll shaft 316, the abutment screw 334 being mounted in a forwardly projecting lug 338 on the swinging arm 294. The downward movement of the retaining rolls under the action of the spring 331 when permitted by the cam 330, is limited by an abutment screw 342 mounted on one of the side frames 130 which is adapted to be engaged by one of the arms 320 that carries the roll shaft 316.

The back tucker 23 (Figs. 1, 10 and 14) comprises a plate having its forward edge portion, when it is in the position shown in Fig. 14, curved outwardly and rearwardly in an arc slightly greater than the radius of the row of articles, and having its bottom side substantially flat. The tucker is provided with upstanding ears 344 which are secured on the shaft 318 that carries the retaining roll 28, the retaining roll being made in sections that are spaced apart so as to receive the ears 344 between them. The shaft 318 is mounted for pivotal movement in the ends of the supporting arms 322, and an arm 346 is secured on the outer end thereof which carries a cam roll or stud 348 that engages a groove 350 in a plate secured to the side frame 130 (Fig. 8).

In Fig. 14 a completed package is shown as about to be removed from between the wrapping rolls by gripping jaws 32 hereinbefore referred to, and also in this figure the gripping jaws 12 are shown as advancing a row of articles toward the wrapping rolls, the row of articles having engaged the upper portion of the wrapper 20 within the basket 22, and carried the wrapper between the back tucker 23 and the upwardly spring pressed plate 24 so as to tightly bend the wrapper about the forward portion of the articles. It may be noted that the engagement of the wrapper with the flat under surface of the back tucker 23 and the flat upwardly spring pressed plate 24, prevents the wrapper from sliding on the articles and becoming crooked. As the row of articles and its wrapper leaves

come in contact with the wrapping rolls 14 and 16, the upper roll 14 is moved downwardly slightly so that as the package is pushed between them, the wrapper is drawn tightly around it, the wrapping rolls being stationary at this time. This slight downward movement of the wrapping roll is permitted by the drop 352 in the cam 330. When the row of articles reaches its position between the wrapping rolls with the axis of the row in the plane of the axes of the wrapping rolls, the retaining fingers 25 are moved inwardly so as to engage the centers of the ends of the row and thus securely hold it in place. At substantially the same time as the retaining fingers 25 engage the ends of the row of articles, a drop 354 in the cam 330 permits the full tension of the downwardly spring pressed rod 332 to be excited to hold the upper wrapping roll 14 firmly down against the articles. The gripping jaws which have been released from the articles by the cross bar 286 when the retaining fingers 25 move inwardly to engage the articles, then back out from between the rolls, and the back tucker 23 moves downwardly, as shown in Fig. 15 to bend the upper edge portion of the wrapper over the articles, and the retaining rolls 26 and 28 move downwardly into engagement with the wrapper at opposite sides of the row, this movement of the back tucker and rolls 26 and 28 being permitted by the cam 330 and said rolls being pressed down under the full tension of their spring 331. The back tucker 23 is held away from actual contact with the package by the roll 28 during its tucking-in movement, the roll 28 offering less resistance than would be offered by the tucker if it pressed against the package. The back tucker, however, is caused by the cam groove 350 to closely follow the peripheral surface of the package as it engages the end of the wrapper and bend it in against the articles. With the parts in the position shown in Fig. 15, the wrapping rolls 14 and 16 are then both rotated in a counter-clockwise direction which rolls the articles and cooperates with the retaining rolls 26 and 28 to cause the wrapper to be tightly wrapped about the peripheral surface thereof.

After the wrapper has thus been completely wrapped about the peripheral surface of the row of articles, the end tucking devices 30 (Figs. 1, 6 and 19) are thrown into operation to tuck the ends of the wrappers in over the ends of the row of articles to complete the wrapping operation. These end tucking devices comprise members that are mounted for rotary movement on the shaft 288 that carries the lower wrapping roll 16, and are pressed toward the ends of the wrapping roll by springs 356 coiled about the shaft and interposed between the ends of the shanks of said members and the side frame 130. Each of these end tucking members are provided

with a series of more or less radially projecting fingers which are suitably arranged and have their advancing faces suitably beveled, that when the tucking members are rotated at substantially the same speed and in the same direction as the lower wrapping roll, the fingers successively engage the wrapper and successively form tucks therein, so that at the completion of one revolution of the tucking members, the ends of the wrapper completely enclose the ends of the articles with a series of successively overlapping tucks, (Figs. 21 to 25, inclusive) the tuck last formed overlying the inner ends of substantially all of the tucks (Fig. 18). As the bevel surfaces of the projecting fingers of the tuckers ride over the tucks and due to the action of the coiled springs 356 that urge the tuckers against the ends of the package, the tucks are firmly pressed out flat. During the revolution of the end tuckers 30 the retaining fingers 25 are withdrawn from the package so that the end tuckers may clear them, but they move in again when the tuckers have passed, for the purpose of holding down the folds of the tucked-in ends of the wrapper. At the completion of this operation the back tucker 23 and the retaining rolls 26 and 28 are lifted nearly to their highest position by the cam 330 to permit the gripping jaws 32, to grip the ends of the package, after which the upper feed roll 14 is lifted to its highest position, as shown in Fig. 14 to permit the package to be removed from the wrapping rolls by said jaws and another to enter.

The end tuckers 30 are rotated, as above described, through connection with the gear 302 (Figs. 5 and 11) through which the lower wrapping roll 16 is driven. This gear 302 is secured on one end of a shaft 366 which extends through and is journaled in a bearing in one of the side frames 130, and carries on its inner end a pinion 368 that engages a gear 370 mounted to rotate on a stud shaft 372. An intermittent or segmental gear 374 (Fig. 8) is secured on the face of the gear 370 and is adapted to intermittently engage a pinion 376 which is secured on a shaft 378 (Fig. 6) having its ends journaled in bearings in the two side frames 130. The shaft 378 is held from turning movement when the segmental gear 374 is out of engagement with the pinion 376 by means of co-operating Geneva disks 380 and 382 secured to the segmental gear and the shaft 378, respectively. The shaft 378 carries gears 371 that operatively engage gears 373 secured on the shanks of the end tuckers 30.

The gripping jaws 32 (Fig. 26) above referred to, for removing the completed package from between the wrapping rolls may be and preferably are of the same construction as the gripping jaws 12, the movable jaw being carried by a spring pressed pin 384 corresponding to the pin 118. These jaws are

adapted to be opened as they approach the completed package by the engagement of the end of the jaw carrying pin 38 with an inclined surface 385 (Fig. 7) on a forward extension of the transverse bar 286, and are permitted to close upon the ends of the package when the retaining fingers 25 release the package, the bar 286 being carried by one of the rods that carries the fingers, as above described. As shown, the gripping jaws are pivotally mounted upon the upper end of a carrier lever 386, and a suitable device including a bell crank 388 corresponding to the bell crank 132, may be employed to swing the jaws in a clockwise direction after they leave the wrapping rolls. The machine, as above described, may be used in connection with a similar wrapping machine for placing a second wrapper over the first wrapper, the second machine being indicated by broken lines in Fig. 26, and it will be apparent that the jaws 32 may be employed to convey the package directly to the wrapping rolls of the second machine.

In the illustrated machine, in case there are less than the desired number of articles delivered at the station adjacent the stop 8, means is provided for interrupting the cycle of operations of the wrapper feed rolls 18 without interrupting the cycle of operations of other parts of the machine, so that while the wrapping mechanism will continue to operate and the article conveying means will complete its cycle of operation, no wrapper will be fed across the path of the gripping jaws 12 during that cycle of operation of the machine and in fact, none will be fed thereafter until a row containing the desired number of articles has been delivered at said station.

To provide for this, an arm 390 (Figs. 1 and 5) is secured on the end of a rock shaft 392 which is suitably mounted in one of the side frames 130. The arm 390 is so positioned that when the feed rolls are at rest, upon the arm being swung in a counter-clockwise direction, viewing Fig. 1, the end of the arm will engage a rearward projection on the ratchet pawl 192 through which the feed rolls are operated, to release the pawl from the ratchet disk. An arm 394 is secured to the other end of the rock shaft 392 and is connected by a rod or link 396 with one arm of a bell crank 398. This bell crank carries a cam roll 400 which engages a cam 402 secured on one end of the shaft 128, the cam roll being pressed toward the cam by means of a coiled spring 404 connected with the bell crank. The outer end of the other arm of the bell crank extends beneath a collar 406 (Fig. 9) secured on the outer end of the rod 80 that carries the collector finger 10. During the operation of the machine, a drop 408 in the cam 402 reaches the cam roll 400 as the collector fingers 10 advance to engage the row of articles. In case there are the desired num-

ber of articles in the row, the end of the bell crank 398 will bring up against the under side of the collar 406, but if there are a less number in the row, the further inward movement of the collector finger rod 80 causes the collar 406 to be moved inwardly a sufficient distance to permit the end of the bell crank to clear it, and thus permit the spring 404 to swing the bell crank a sufficient distance to act through the link 396, to swing the arm 390 in a direction to strike the projection on the ratchet pawl 192 and disconnect the ratchet pawl from the ratchet disk thus throwing and maintaining the wrapper feeding mechanism out of operation during that cycle of operation of the machine. When, however, the short row of articles has been discharged from the machine, as hereinbefore described, and another row has been delivered to the station adjacent the stop member 8, if this row contains the desired number of articles then the wrapper feeding mechanism is permitted to operate during the next cycle of operation of the machine, but if there is a less number of articles in the row, the wrapper feeding mechanism will again be rendered inoperative.

In case a second wrapping machine is employed, as illustrated in Fig. 26, it is of course desirable that the wrapper feeding mechanism of that machine shall be thrown out of operation, when a package is not delivered to the machine during a cycle of operation thereof, which would occur if a row of articles containing less than the desired number were delivered to the station adjacent the stop member 8 and discharged from the first machine. To provide for this an arm 410 is rigidly secured to the projection 338 of the swinging block or arm 294 that carries the upper feed roll. This arm 410 is connected by a link 412 to one end of a lever 414 which is pivoted at 416 to the frame of the second machine. The forward end of this lever is so positioned that in case the first machine fails to deliver a row of articles to the wrapping rolls thereof during one cycle of operation, the excessive downward movement of the upper wrapping roll through the action of the spring connected therewith acts through the link 412 to cause the end of the lever 414 to engage the projection on the end of the ratchet pawl that drives the wrapper feeding mechanism of the second machine and thus throw the wrapper feeding mechanism out of operation for that cycle of operation of the machine, such mechanism being substantially the same as that above described of the first machine.

In the modified form of wrapping mechanism illustrated in Figs. 27, 28 and 29, there are employed upper and lower feed rolls 420 and 422, and retaining rolls 424 which are arranged similarly to the corresponding parts of the mechanism first described. In this

construction, however, end tucker members 426 are pivotally mounted on pins 428 that are mounted in bearing plates 430 secured directly to the ends of the wrapping roll. These tucker members are pressed toward the ends of the roll so as to cause their projecting tucker fingers 432 to press against the ends of the package as the tucks are being formed, by means of springs 434 coiled about the ends of the pivot pins, and each having one end secured to the tucker member and its other end secured to the wrapping roll. In this construction, the lower wrapping roll is made of sufficiently large diameter so that the peripheral surface thereof is given an opportunity to rotate the package sufficiently to cause the wrapper to be laid about its peripheral surface before the end tucker members are brought into engagement with the ends of the wrapper. Also in the construction shown, instead of the wrapper being cut off from the downwardly fed strip prior to the engagement therewith of the advancing row of articles, the construction is such that the gripping jaws carry the row of articles against the lower portion of the strip and in between the wrapping rolls, and back tucking members 436 act to bend the end of the strip upwardly over the back of the row before the knives 438 act to cut off the wrapper. After the back tucking members 436 act and the wrapper is cut off, the retaining rolls 424 move downwardly into engagement with the partially wrapped article, and then the wrapping rolls act to complete the laying of the wrapper about the cylindrical surface of the article, preparatory to the end tucking operation as above described. The back tucking members 436 are formed on the upper end of flat rods 440, each of which has its lower end guided by a roll 442 that is received in a guiding slot 444 in a bracket on the base of the machine. The rods are actuated by means of a cam 446, that engages a cam roll on a lever 448 which has one end pivotally connected with the several rods 440, the cam roll being held in engagement with the cam by means of a coiled spring 450 connected with the other end of the lever. The lower feed roll 422 is provided with annular clearance grooves 452 through which the upper end portions of the rods 440 extend so as to permit the back tucking members 436 to be properly positioned.

The article handling mechanism illustrated in Figs. 30, 31 and 32 is adapted to be attached to the machine above described. In Fig. 30 is shown the shaft 128, the conveyor lever 114, the gripping jaws 12, and the rocker arm 72, of said machine. In this mechanism, however, a turret 453 is employed for conveying the articles from supply chutes 454 to a position to permit them to be engaged by the gripping jaws 12 and transferred to the wrapping mechanism. The turret is mounted upon

a shaft 456 which is intermittently driven from the shaft 128 through suitable mechanism which may comprise a sprocket chain 458 that passes over sprocket wheels on the shaft 128 and a countershaft 460, and a Geneva mechanism 462 that connects the shaft 460 with a shaft 464 having a pinion 466 secured thereon that engages a gear 468 secured on the turret shaft 456. The turret 453 is provided with a series of transverse pockets 470 which, during each movement of the turret, successively move up through a slot in the bottom wall 472 of the chutes and into alinement with upstanding end pieces 474 secured to the bottom of the chutes. When a pocket reaches this position, a row of articles is permitted to drop by gravity into the receptacle formed by the pocket and said end pieces 474. When a row is thus positioned, collector members 476 move inwardly to engage the endmost articles in the row so as to bring the articles together, which positions the ends of the row substantially flush with the sides of the turret. The collector members 476 are formed upon the ends of levers 478 and 480 that are connected by a link 482 to work together, and are actuated by any suitable mechanism. The articles are held in the pockets after they leave the collector members 476 during the rotation of the turret, by side plates 484 which are secured to the frame of the machine. When one pocket is moved into position to receive a row of articles from the chutes, the fourth pocket in advance thereof is in position to permit the gripping jaws 12 to remove the row of articles therefrom and to carry it to the wrapping mechanism. As the rows of articles are carried step by step from the chutes to the gripping jaws they are in full view of the operator of the machine, and in case it is found that there are not the desired number of articles in any one row, he may easily slip the additional number required in place.

45 As will be evident to those skilled in the art, my invention permits various modifications without departing from the spirit thereof or the scope of the appended claims.

What I claim is:

50 1. A machine for wrapping articles of the class described having, in combination, means for arranging a plurality of articles side by side and spaced apart, a device for holding the articles at the station where they are thus arranged, devices for bringing the articles together in a row, means acting automatically to convey the row to another station in case there are a predetermined number of articles in the row, mechanism for placing a wrapper about the row of articles while the articles are at the latter station, and means acting automatically to release said holding device to permit the row of articles 60 to be discharged from the machine in case

there are less than said predetermined number of articles in the row.

2. A machine for wrapping articles of the class described having, in combination, a support for an article, means for conveying the article to another station comprising gripping jaws adapted to be relatively moved toward and from each other to engage and disengage the ends of the article, a spring tending to close the jaws, means comprising a carrier for the jaws for moving them into position to permit them to grip the ends of the article and for moving them away from said position, and means for effecting the opening of the jaws against the action of said spring during their movement toward said position, and for permitting them to close when they reach said position, and mechanism for placing a wrapper about the article while said article is at the second mentioned station.

3. A machine for wrapping articles of the class described having, in combination, means for assembling the articles side by side in a row at one station, means for conveying the articles to another station comprising gripping jaws adapted to be relatively moved toward and from each other to engage and disengage the ends of the row, a stop for limiting the closing of the jaws so as to prevent them from gripping the ends of the row in case there are less than a predetermined number of articles in the row, a spring tending to close the jaws, means comprising a carrier for the jaws for moving them into position to permit them to grip the ends of the row, and for moving them away from said position, and means for effecting the opening of the jaws against the action of said spring during their movement toward said position, and for permitting them to close when they reach said position, and mechanism for placing a wrapper about the row of articles while the row is at the second mentioned station.

4. A machine for wrapping articles of the class described having, in combination, means for arranging a plurality of articles side by side and spaced apart at one station, devices for engaging the endmost articles to bring the articles together in a row and after a predetermined interval to release said row, means acting to grip the ends of the row while the row is held by said devices, and to convey the row toward another station after said devices release said row, and mechanism for placing a wrapper about said row of articles while the row is at the second mentioned station.

5. A machine for wrapping articles of the class described having, in combination, a plurality of downwardly inclined chutes for receiving the articles with the articles in each chute arranged in upright position one behind the other, an escapement adapted to be moved to engage the lowermost articles in

the several chutes to limit the downward movement thereof, to release said lowermost articles to permit the articles in the several chutes to advance, to reengage said lowermost articles to limit said advancing movement thereof, to release said lowermost articles to permit them to advance independently of the other articles in the raceways and to engage the next succeeding articles in the several raceways to limit their advancing movement, a stop for limiting the last-mentioned advancing movement of said lowermost articles adapted to be retracted to permit said articles to be discharged from the machine, means comprising gripping jaws adapted to be operated to convey the row of articles thus delivered into engagement with said stop to another station provided there are a predetermined number of said articles, 20 and incapable of conveying the articles provided there are a less number, means for actuating said escapement and said stop in timed relation to said gripping jaws, and mechanism for placing a wrapper about the 25 row of articles while the row is at the second mentioned station.

6. A machine for wrapping articles having, in combination, means for arranging a plurality of articles side by side in a row at 30 one station, a conveyor for conveying the row to another station provided there are a predetermined number of articles in the row but incapable of thus conveying the articles if there are a less number in the row, means for 35 effecting the discharge of the articles from the machine in case there are less than said predetermined number in the row, and mechanism for placing a wrapper about said row while the row is at the second mentioned station.

7. A machine for wrapping articles of the class described having, in combination, a support for a plurality of articles arranged side by side in a row, devices adapted to be operated to detect whether or not there are a predetermined number of articles in the row, means for thus operating said devices, means for conveying the articles from said support to another station provided there are said 50 predetermined number of articles in the row, but incapable of thus conveying the articles if there are a less number in the row, mechanism for placing a wrapper about the row of articles when delivered to said station, feeding means for presenting the wrapper to said wrapping mechanism, and means controllable by said detecting devices for rendering said feeding means inoperative to present said wrapper in case there are less than said 55 predetermined number of articles in the row.

8. A machine for wrapping articles of the class described having, in combination, a support for a plurality of articles arranged side by side and spaced apart, devices for bringing the articles together in a row and detect-

ing whether or not there are a predetermined number of articles in the row, means for thus operating said devices, wrapper feeding means, mechanism for placing the wrapper about a row of articles delivered thereto, 70 means for conveying the row of articles from said support to said wrapping mechanism provided there are a predetermined number of articles in the row but incapable of thus conveying the articles if there are a less number in the row, means for operating said feeding means capable of being thrown out of operation independently of said wrapping mechanism and means controllable by said devices for thus throwing said feeding means 75 out of operation in case there are less than said predetermined number of articles in said row.

9. A machine for wrapping articles of the class described having, in combination, a support for a plurality of articles arranged side by side in a row, devices for detecting whether or not there are a predetermined number of articles in the row, wrapping rolls, means for conveying the row of articles from said support to said wrapping rolls provided there are a predetermined number of articles in the row but incapable of thus conveying the articles provided there are a less number in the row, means for delivering a wrapper 90 across the path of the movement of the row and adjacent to the wrapping rolls, whereby the row of articles in its movement to the wrapping rolls will carry the paper therewith to said wrapping rolls, mechanism for operating said wrapper feeding means capable of being thrown out of operation independently of the operation of said wrapping rolls, and means controllable by said detecting devices for throwing said mechanism out of operation in case the row of articles has less than said predetermined number therein.

10. A machine for wrapping articles of the class described having, in combination, a support for a plurality of articles arranged side by side in a row, devices adapted to be operated to detect whether or not there are a predetermined number of articles in the row, means for thus operating said devices, wrapping rolls, means for conveying the articles from said support to said wrapping rolls provided there are said predetermined number of articles in the row but incapable of thus conveying the articles if there are a less number in the row, means for feeding wrapping material across the path of the articles during their travel from said support to the wrapping rolls and for cutting off a sheet of suitable size to wrap about the row of articles, mechanism for operating said feeding means capable of being thrown out of operation independently of the operation of said conveying means, and means controllable by said detecting devices for throwing said mechanism out of operation in case there are less 125

than said predetermined number of articles in the row.

11. A machine for wrapping an article of cylindrical form having, in combination, 5 wrapping rolls arranged in parallel relation and spaced apart one above the other for receiving the article between them, means for conveying the article to the wrapping rolls, means for feeding completed wrapper down- 10 wardly across the path of said article whereby the wrapper is carried by the article to the wrapping rolls, means for rotating the wrapping rolls when the article and wrapper has been delivered between them, and means for 15 holding the article between the rolls during the rotation of the rolls.

12. A machine for wrapping an article of cylindrical form having, in combination, wrapping rolls arranged in parallel relation 20 and spaced apart one above the other, means for conveying the article between the rolls with the axis of the article arranged substantially in the plane of the axes of the rolls, means for maintaining the article in position 25 between the rolls, means for delivering a wrapper across the path of the article whereby it is carried by the article to said rolls, means for tucking one edge portion of the wrapper over the article after the article has 30 substantially reached said position between the rolls, and mechanism for suitably actuating said rolls while said tucked-in portion is held in position to cause the wrapper to be wrapped about the article.

35 13. A machine for wrapping an article of cylindrical form having, in combination, wrapping rolls arranged in parallel relation and spaced apart one above the other, means for conveying the article to a position be- 40 tween the rolls with the axis of the article substantially in the plane of the axes of the rolls, means for maintaining the article in position between the rolls, means for delivering a wrapper across the path of the article 45 whereby it is carried by the article to the rolls, devices for wiping the wrapper tightly about the forward portion of the peripheral surface of the article, and for tucking in one edge portion of the wrapper when the article 50 reaches said position between the rolls, and mechanism for suitably actuating the rolls while said tucked-in portion is held in position to cause the wrapper to be wrapped about the article.

55 14. A machine for wrapping an article of cylindrical form having, in combination, wrapping rolls arranged in parallel relation and spaced apart, means for conveying the article to a position between the rolls with the 60 axis of the article substantially in the plane of the axes of the rolls, a spring and suitable connections for moving the rolls toward each other a slight distance as the article approaches the rolls so as to cause the rolls to 65 apply a yielding pressure on the article as it

enters its position between them, means for delivering a wrapper to the rolls and article, means for holding the article in position between the rolls, and means for suitably rotating the rolls while the article is held between them to cause the wrapper to be wrapped about the article. 70

15. A machine for wrapping an article of cylindrical form having, in combination, 75 means for bending a wrapper over substantially one-half of the peripheral surface of the article, means for tucking one edge portion of the wrapper inwardly over the article, means for bringing the other edge portion of the wrapper about the article and over said 80 first mentioned edge portion so as to completely wrap the article, and means for tucking the ends of the wrapper over the ends of the article and for yieldingly pressing said tucked in ends against the ends of the article. 85

16. A machine for wrapping an article of cylindrical form having, in combination, means for placing a wrapper about the peripheral surface of the article with the ends of the wrapper projecting beyond the ends of the article, a device for tucking in each end of the wrapper over the corresponding end of the article to form a plurality of tucks that successively overlap each other, and means for yieldingly pressing said device 90 against the end of the article during the tucking operation.

17. A machine for wrapping an article of cylindrical form having, in combination, 100 means for placing a wrapper about the peripheral surface of the article comprising wrapping rolls arranged in parallel relation and spaced apart for receiving the article with its wrapper between them with the axis of the article arranged substantially in the plane of the axes of the rolls, and means for rotating the rolls a predetermined number of times, and a rotatable device arranged concentrically with one of the rolls and capable of being thrown into operation during the 105 rotation of the rolls after the wrapper has been wound at least once around the article to form a plurality of tucks in the adjacent end of the wrapper that successively overlap the end of the article, and means for thus actuating said device. 110

18. A machine for wrapping an article of cylindrical form having, in combination, 115 wrapping rolls arranged in parallel relation and spaced apart for receiving the article with its wrapper between them with the axis of the article arranged substantially in the plane of the axes of the rolls, and adapted upon rotation to apply the wrapper about the peripheral surface of the article while held in said position, a device arranged concentrically with the axis of at least one of the rolls having a series of substantially radially projecting fingers constructed to form a plurality of tucks in the projecting end of the 120 125 130

wrapper that successively overlap each other during the rotation of the rolls, said tucking fingers initially operating effectively after the wrapper has been wound at least once around the article and means for actuating said rolls and said device.

19. A machine for wrapping an article of cylindrical form having, in combination, means for placing a wrapper about the peripheral surface of the article with the ends of the wrapper projecting beyond the ends of the article, comprising a wrapping roll and suitable devices for holding the article and wrapper in contact with the roll with the axis of the article substantially parallel to the axis of the roll whereby the article and wrapper are rotated upon rotation of the roll, means for rotating said roll, and devices arranged adjacent opposite ends of said roll acting upon rotation thereof and during the rotation of the article to tuck in the ends of the wrapper over the ends of the article so as to form a plurality of successively overlapping tucks in each end of the wrapper, said devices being initially operated effectively after the wrapper has been wound at least once around the article.

20. A machine for wrapping an article of cylindrical form having, in combination, means for placing a wrapper about the peripheral surface of the article with the ends of the wrapper projecting beyond the ends of the article, comprising a wrapping roll and suitable devices for holding the article and wrapper in contact with the roll with the axis of the article substantially parallel to the axis of the roll whereby the article and wrapper are rotated upon rotation of the roll, means for rotating said roll, and devices arranged adjacent the ends of the roll and having a plurality of outwardly projecting fingers adapted upon rotation of said devices during the rotation of said roll to form a plurality of overlapping tucks in each projecting end of the wrapper, and means for causing said devices to yieldingly press against the ends of the article during the effective operation thereof.

21. A machine for wrapping an article of substantially cylindrical form having, in combination, means for placing the wrapper about the cylindrical surface of the article, comprising wrapping rolls arranged in parallel relation and spaced apart one above the other adapted to receive the article between them with the axis of the article substantially in the plane of the axes of the rolls, devices for engaging the ends of the article to hold the article in said position but permitting it to be rotated upon rotation of said rolls, means for yieldingly pressing the rolls towards each other to cause them to apply pressure to the article during the rotation thereof, and means for rotating the rolls.

22. A machine for wrapping an article of

substantially cylindrical form having, in combination, means for placing a wrapper about the cylindrical surface of the article comprising wrapping rolls arranged in parallel relation and spaced apart one above the other for receiving the article between them and to rotate the article upon rotation thereof, devices for engaging opposite sides of the cylindrical surface of the article when the article has thus been placed between the rolls for preventing lateral movement of the article, means for rotating said rolls to rotate the article a predetermined number of degrees, and means for retracting said devices from the article after said operation of said rolls to permit the article to be removed from its position between the rolls.

23. A machine for wrapping an article of cylindrical form having, in combination, means for placing a wrapper about the cylindrical surface of the article comprising a pair of wrapping rolls arranged in parallel relation and adapted to receive the article between them with the axis of the article in the plane of the axes of the rolls, a second pair of rolls for engaging opposite sides of the cylindrical surface of the article after the article has been positioned between the rolls, means for causing the several rolls to yieldingly grip the article, means for effecting the rotation of said first mentioned pair of rolls a predetermined number of times, and means for retracting the second mentioned pair of rolls from the article after said operation of the first mentioned pair of rolls.

24. A machine for wrapping an article of cylindrical form having, in combination, wrapping rolls arranged in parallel relation and spaced apart, means for presenting the article and its wrapper to the wrapping rolls with the axis of the article in the plane of the axes of the rolls, retaining rolls adapted to engage opposite sides of the article after it is delivered between the rolls, means for relatively pressing said wrapping rolls toward each other to cause them to yieldingly grip the article, means for rotating said rolls, and means for moving said retaining rolls toward and from said article.

25. A machine for wrapping an article of cylindrical form having, in combination, wrapping rolls arranged in parallel relation and spaced apart for receiving the article between them with the axis of the article arranged substantially in the plane of the axes of the rolls, retaining rolls adapted to engage opposite sides of the article when placed in said position between the wrapping rolls, and means for relatively moving the wrapping rolls toward each other to cause them to grip the article, and for simultaneously moving said retaining rolls toward the article.

26. A machine for wrapping an article of cylindrical form having, in combination, means for placing a wrapper about the pe-

- ripheral surface of the article with the ends of the wrapper projecting beyond the ends of the article, comprising a wrapping roll and suitable devices for holding the article and 5 wrapper in contact with the roll with the axis of the article substantially parallel to the axis of the roll whereby the article and wrapper are rotated upon rotation of the roll, and devices acting during the continued rotation of the wrapping roll and article and after the wrapper has been wound at least once around the article to tuck in the ends of the wrapper over the ends of the article so as to cause the ends of the wrapper to completely cover the ends of the article.
27. A machine for wrapping an article of cylindrical form having, in combination, means comprising rotatable wrapping rolls for wrapping a wrapper around the peripheral surface of an article with the ends of the wrapper projecting beyond the ends of the article, and rotatable devices mounted concentrically of one of the rolls for tucking in the ends of said wrapper over the ends of 20 the article during the rotation of the article and after the wrapper has been wound at least once around the article.
28. A machine for wrapping an article of cylindrical form having, in combination, 30 means comprising rotatable wrapping rolls for wrapping a wrapper around the peripheral surface of the article with the ends of the wrapper projecting beyond the ends of the article, rotatable devices mounted concentrically of one of the rolls for tucking in the ends of said wrapper over the ends of the article during the rotation of the article, and means for yieldingly pressing said devices against the ends of the article.
29. A machine for wrapping an article of cylindrical form having, in combination, 40 means comprising rotatable wrapping rolls for wrapping a wrapper around the peripheral surface of the article with the ends of the wrapper projecting beyond the ends of the article, said rolls being held in substantially fixed position with relation to their axes during their effective operation, and rotatable devices mounted concentrically on 45 one of the rolls and rotated in the same direction as the roll for tucking in the ends of the wrapper over the ends of the article during the continued rotation of said roll and article and after the wrapper has been wrapped at least once around the article.
30. A machine for wrapping an article of cylindrical form having, in combination, 50 means comprising rotatable wrapping rolls for wrapping a wrapper around the peripheral surface of the article with the ends of the wrapper projecting beyond the ends of the article, and rotatable devices mounted concentrically of one of the rolls and rotated in 55 the same direction and at substantially the same speed as the roll for tucking in the ends of the wrapper over the ends of the article during the continued rotation of said roll and article and after the wrapper has been wrapped at least once around the article.
31. In a machine for wrapping articles of the type in which an article is conveyed from a support to another station where mechanism acts to place a wrapper about the article, the improvement which consists in the means for conveying the article which comprises a carrier lever, gripping jaws pivotally mounted on the lever to swing about an axis substantially parallel with the axis of the lever and capable of being opened as they approach said support and being closed as they reach a position to grip said article, means for turning said lever in opposite directions to move the jaws toward and from said support, and means for turning the jaws about the axis of their pivotal connection with the lever during the movement of the lever, comprising a gear segment pivotally mounted on the lever, a pinion in operative engagement with the gear segment and mounted to turn with the jaws, and means for turning the gear segment during the movement of said lever.
32. A machine for wrapping an article of substantially cylindrical form having, in combination, wrapping rolls arranged parallel and spaced apart for receiving the article and its wrapper between them, and means for relatively moving the rolls toward each other and retaining them in position so as to cause them to yieldingly resist the positioning of an article between them, to bear on the article under increased pressure after the article has been positioned between them and during the wrapping operation, and for relatively moving the rolls away from each other after the completion of the wrapping operation.
33. A machine for wrapping a cylindrical article having, in combination, a support for the article, devices adapted to be operated to detect whether or not the article is of a predetermined length, means for thus operating said devices, means for conveying the article from said support to another station provided the article is of a predetermined length but incapable of thus conveying the article if the article is of less than said predetermined length, mechanism for placing a wrapper about the article when delivered to said station, feeding means for presenting the wrapper to said wrapping mechanism, and means controllable by said detecting devices for rendering said feeding means inoperative to present said wrapper in case the article is less than said predetermined length.
- In testimony whereof, I have signed my name to this specification this 8th day of December, 1925.
- HARRY E. TOWNSEND.
